DESIGN FOR A LIGHTER CASE OR SIMILAR ARTICLE

James H. Horsley, Chicago, Ill., assignor to Park Sherman Co., Inc., Chicago, Ill., a corporation of Illinois

Application April 22, 1944, Serial No. 113,335

Term of patent 14 years

(Cl. D48—27)

To all whom it may concern:

Be it known that I, James H. Horsley, a citizen of the United States, residing at Chicago, in the county of Cook and State of Illinois, have invented a new, original, and ornamental Design for Lighter Case or Similar Article, of which the following is a specification, reference being had to the accompanying drawing, forming a part thereof.

In the drawing:

or similar article showing my new design as viewed from right to left.

The back of the case, not shown, is a substantial duplicate of the face illustrated.

I claim:

The ornamental design for a lighter case or similar article, substantially as shown and described.

JAMES H. HORSLEY.
